DESIGN FOR A MAT OR SIMILAR ARTICLE

Stephen Andrew Kowalski, South Bend, Ind.

Application March 5, 1942, Serial No. 106,092

Term of patent 14 years

To all whom it may concern:

Be it known that I, Stephen Andrew Kowalski, a citizen of the United States, residing at South Bend, in the county of St. Joseph and State of Indiana, have invented a new, original, and ornamental Design for a Mat or Similar Article, of which the following is a specification, reference being had to the accompanying drawing, forming part thereof.

side thereof, and

Figure 4 is an end elevational view.

I claim:

The ornamental design for a mat or similar article, as shown.

STEPHEN A. KOWALSKI.
